Primary Examiner — Susan E Krakower*Assistant Examiner* — Lisa A Grabenstetter(74) *Attorney, Agent, or Firm* — Faegre Baker Daniels LLP(57) **CLAIM**

The ornamental design for a hexagonal inflatable spa, as shown and described.

DESCRIPTION

FIG. 1 is a perspective view of a hexagonal inflatable spa showing our new design;

FIG. 2 is a first side elevational view thereof;

FIG. 3 is a second side elevational view thereof;

FIG. 4 is a top plan view thereof; and,

FIG. 5 is a bottom plan view thereof.

The broken lines in FIGS. 1-5 represent unclaimed portions of the hexagonal inflatable spa and form no part of the claimed design.

1 Claim, 5 Drawing Sheets(56)
